[57] CLAIM

The ornamental design for a coffee table, as shown and described.

DESCRIPTION

FIG. 1 is a perspective view of a coffee table embodying the new design;

FIG. 2 is an end elevation of the coffee table shown in FIG. 1;

FIG. 3 is a side elevation of the coffee table shown in FIG. 1; and

FIG. 4 is a bottom plan view of the coffee table shown in FIG. 1.

The end and side of the table not shown are the same in appearance as the respective end and side shown in FIG. 1.
